VALVE

Robert S. Keane, Placentia, Calif., assignor to International Research Corp., Anaheim, Calif., a corporation of California

Filed May 24, 1966, Ser. No. 2,415

Term of patent 14 years

(Cl. D91—3)

FIG. 1.

FIG. 2.

FIG. 3.

FIG. 4.

FIG. 1 is a perspective view looking down at one end and one side of a valve showing my new design;

FIG. 2 is a perspective view thereof looking upwardly at the other end and the other side of the valve;

FIG. 3 is a perspective view corresponding to FIG. 1, of a modified form of the valve; and

FIG. 4 is a perspective view corresponding to FIG. 2 of the modified form of the valve shown in FIG. 3.

I claim:

The ornamental design for a valve, as shown and described.
